CLAIM

The ornamental design for an automated pharmacy machine, as shown and described.

DESCRIPTION

FIG. 1 is a front perspective view of an automated pharmacy machine showing our design;

FIG. 2 is a rear perspective view of the automated pharmacy machine of FIG. 1;

FIG. 3 is a front view thereof;

FIG. 4 is a rear view thereof;

FIG. 5 is a side view thereof;

FIG. 6 is an opposing side view thereof; and,

FIG. 7 is a top view thereof.

The broken lines shown herein are for illustrative purposes only and form no part of the claimed design.
